UNITED STATES PATENT OFFICE

JOHN F. MAKOWSKI, OF OAKLAND, CALIFORNIA, ASSIGNOR TO FIREPROOF WALL COMPANY, OF RENO, NEVADA, A CORPORATION OF NEVADA

CONDUIT CUTTING APPARATUS

Application filed July 16, 1929. Serial No. 378,658.

This invention relates to the manufacture of tubular clay products such as cable conduit, sewer tile, drain tile, water pipe etc. and particularly to a means for cutting the plastic tubes into sections of predetermined lengths as they emerge from the press or forming machine in which they are made.

In tubular products of this character, particularly cable conduit, it is essential that there be no deformation of the cross sectional area thereof and that there be no rough edges or projections about the periphery. The usual form of cutting means however, such as wires and the like, operated from outside the tubular members, have a strong tendency to flatten or deform the same and also invariably leave a certain projecting roughness about the cut edges.

The principal object of my invention is to avoid this deformation and roughness by providing a cutting means disposed inside the conduit and arranged to cut from the bore outwardly; and which as it cuts forms a smooth chamfer about the bore on both sides of and immediately adjacent the line of cut.

A further object is to mount the cutter so that it may be easily withdrawn from a cut section or length of conduit to enable the latter to be withdrawn from association with the cutting apparatus, and another length to be then fed into place to be cut.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a sectional elevation of my improved cutting apparatus as operating on a length of conduit.

Fig. 2 is an enlarged elevation partly in section of the cutting unit detached.

Fig. 3 is an enlarged cross section taken substantially on the line 3—3 of Fig. 1.

Fig. 4 is a rear end view of the cutting unit showing the position of the operating handle when the cutter is in its cutting position.

Fig. 5 is a cross-section of the apparatus as taken on the line 5—5 of Fig. 1 showing the cutter retracted from its operative position.

Fig. 6 is a rear end view of the cutter unit showing the position of the operating handle when the cutter is retracted or inoperative.

Referring now more particularly to the characters of reference on the drawings, the apparatus comprises a horizontal support 1 having a fixed trough 2 toward one end along which the conduit C as it is formed is fed from the forming machine which is preferably of that character shown in my copending application for patent Serial No. 278,786 filed May 18th, 1928. This trough terminates at a block unit 3 fixed on the support 1, which unit is orificed concentric with the trough to enable the conduit to pass therethrough. The upper portion 3a of this unit is split on the horizontal diametral line of the orifice and is removable from the lower portion, being slidably mounted on vertical pins 4 projecting upwardly from the latter. Some distance beyond the block 3 a stop block 5 is fixed on the support 1, which block 5 has a central orifice 6 therethrough concentric with that of the block 3 but of insufficient size to allow the conduit to pass through the same. Between the blocks the formed conduit as it advances is supported on a removable cradle 7 which rests on supports 8 disposed adjacent said blocks.

Disposed beyond the block 5 are longitudinally spaced bearings 9 in which a hollow cylindrical bar 10 is both turnable and slideable. This bar has collars 11 on both ends

limiting the sliding movement of the bar relative to the bearings in both directions.

Turnable in bearings 12 mounted in the ends of the bar is a shaft 13, offset or eccentric relative to the axis of the bar and projecting beyond the ends of the same. On one end of the shaft outwardly of the bearings 9 a crank handle 14 is fixed, while on the other end of the shaft a relatively short crank 15 is secured. On the outer end of the crank a disc cutter 16 is turnably mounted, the diameter of this disc being somewhat smaller than the orifice 6 and of course smaller than the bore of the conduit. The crank is proportioned so that when it is turned to a certain position the disc will be concentric with the bar and when turned to a point substantially diametrically opposed to such position the outer periphery of the disc is then in the plane of the outer periphery of the conduit. Opposed stops 17 project outwardly from the collar 11 nearest the handle to engage the latter. These stops are positioned so that when the handle is turned clockwise or in a right-hand direction to engage one stop the disc will be in a cutting position; and when said handle is turned a certain amount in the opposite or in an anti-clockwise direction to engage the other stop the disc will then be in a retracted or centralized position relative to the bar.

Bevel or sloping faced discs 18 of smaller diameter than the cutting disc are mounted in close connection therewith on both sides of the same, being of such size relative to the thickness of the conduit as to cause a bevel or chamfer as at 19 to be depressed in the bore of the conduit adjacent and on both sides of the plane of the cut. The length of the bar is such that when the collar 11 at the outer end abuts against the adjacent bearing 9 the cutting disc is positioned substantially midway between the ends of the block 3. When the bar is slid lengthwise so that the other stop abuts against the other bearing 9 the disc is then housed in by and does not project beyond the block 5. This is the normal or inoperative position of the cutting device when not in use or when a cut length of conduit is being removed, and the cutting disc being then enclosed by the said block there is no danger of an operator coming in contact with the disc and being hurt.

In operation the conduit as it is formed is fed from the machine until it abuts against the block 5 which of course limits its advancing movement. While the conduit is being thus advanced the cutting disc is moved to its centralized inoperative position and the bar is retracted so that the disc is enclosed by the block 5. The bar is then advanced to its limit of movement inside the conduit and when fully advanced the handle 14 is rotated so as to throw the disc into eccentric relation to the bar and into a cutting position. By the time

the handle abuts against the corresponding stop 17 the cutter has been pressed through the still soft material of the conduit to the outer periphery of the same and a further turning of the handle in the same direction, after abutting against said stop, causes the bar and disc to be rotated as a unit without movement of one relative to the other. The disc therefore retains its eccentric relation to the bar and the conduit is cut through its entire circumference. At the same time the bevel discs 18 press the desired chamfers in the conduit as previously explained. The plane of cutting being in the block 3 the latter prevents the material being forced outwardly of the periphery of the conduit and gives a clean edged appearance to the cut.

The cut having been made the handle 14 is rotated in the opposite direction to retract the disc to its central position, and the bar is then withdrawn to its opposite limit of movement. The upper block member 3a is then withdrawn which permits the cutting section with its supporting cradle 7 to be removed together and stacked in a suitable location until dry. Another cradle 7 is then placed in position, the block 3a is replaced and the conduit may then be further advanced so as to enable another cutting operation to be effected.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A device for cutting a tubular member into lengths including a support for the member, a bar, means beyond said support slidably and turnably supporting said bar in concentric relation with the supported member, a stop for the member between the bar and member supports and through which one end of said bar may project, a cutting disc at said end of the bar of smaller diameter than the bore of the member, means supporting said disc from the bar to enable the disc being placed concentric with or eccentric to said bar and member, and means operable from the opposite end of the bar for thus selectively positioning the disc, and means between said bar and operating means to enable the bar to be rotated when the disc is eccentrically positioned.

2. A device for cutting a tubular member into lengths including a turnable bar adapted to be projected from its outer end into the member concentric therewith, a shaft turn-

ably mounted in and extending through the bar in eccentric relation to the axis of the bar, a crank on the shaft at the outer end of the bar, a cutting disc mounted on the outer end 5 of the crank, the axis of the disc relative to that of the shaft and bar being such that a turning of the crank to a certain position will place the disc concentric with the bar, and a turning of the crank to another position will 10 move the outer periphery of the disc into the plane of the outer periphery of the member, a handle on the opposite end of the shaft for rotating the same, and stop means between the bar and handle limiting the rotation of the 15 shaft in either direction independently of the bar to an arcuate amount corresponding to the arcuate movement of the crank between its two positions.

3. A device for cutting a tubular member 20 into lengths including a turnable bar adapted to be projected from its outer end into the member concentric therewith, a shaft turnably mounted in and extending through the bar in eccentric relation to the axis of the 25 bar, a crank on the shaft at the outer end of the bar, a cutting disc mounted on the outer end of the crank, the axis of the disc relative to that of the shaft and bar being such that a turning of the crank to a certain 30 position will place the disc concentric with the bar, and a turning of the crank to another position will move the outer periphery of the disc into the plane of the outer periphery of the member, and means operable from the 35 other end of the bar for selectively moving the crank and disc to said position.

4. A device for cutting a tubular member 40 into lengths including a turnable bar adapted to be projected from its outer end into the member concentric therewith, a shaft turnably mounted in and extending through the bar in eccentric relation to the axis of the bar, a crank on the shaft at the outer end of the bar, a cutting disc mounted on the outer end 45 of the crank, the axis of the disc relative to that of the shaft and bar being such that a turning of the crank to a certain position will place the disc concentric with the bar and a turning of the crank to another position 50 will move the outer periphery of the disc into the plane of the outer periphery of the member, means operable from the other end of the bar for selectively moving the crank and disc to said position, and means between the 55 bar and operating means for enabling the bar and crank to be rotated as a relatively immovable unit when said crank has been moved to place the disc in said eccentric position.

5. A cutter unit comprising a bar, a shaft 60 eccentric to the bar and rotatable therein, a crank on the shaft having the axis of its outer end normally concentric with the bar, a cutting blade on said outer end of the crank, and means to limit the independent rotation 65

of said shaft within the bar in either direction.

6. Means for cutting a tubular member 70 into lengths comprising supporting means for a definite length of said member, a block unit to closely surround said member at one end of the supporting means and including a removable cap portion, and means insertible in and removable from the end of the member opposite the block for cutting the member 75 through circumferentially and from the inside out, and means to locate the cutting means when in operation in a longitudinal plane intermediate the ends of the block unit.

7. Means for cutting a tubular member 80 into lengths comprising supporting means for a definite length of said member, a bar projectable into the supported member from its outer end, a cutter on that end of the bar which is adapted to be thus projected, said cutter being arranged to engage and cut the member through circumferentially from the inside out; bearing means for the bar beyond the member supporting means in which said bar is both turnable and slidable, 85 said bearing means being arranged to maintain the bar axially alined with the member and to permit said bar being completely withdrawn from such member.

8. A cutter for a tubular member comprising 90 a cutting element, a support for the element, means in which said support is mounted adapted to be moved lengthwise into the member from the outer end thereof, and means between said support and the first 95 named means for positively moving said element into cutting relationship with the interior periphery of the member and for then rotating the element with the axis of the member as the axis of rotation of the element.

9. A cutter for a tubular member comprising 100 a cutting element, a support for the element, a turnable bar in which said support is mounted adapted to be moved lengthwise into the member from its outer end, and means between the support and bar for first 105 moving the support to a position such that the cutting element engages the member, and for then rotating the bar, in one continuous operation.

10. A cutting device for a tubular member comprising a support for the member, a bar mounted in connection with the support for turning and longitudinal movement and disposed in axial alinement with a supported member, a shaft eccentrically and turnably mounted in the bar, a crank on the shaft outwardly of the bar having its outer axis normally concentric with the bar, a cutting disc mounted on said axis of lesser diameter than the bore of the member, and means for turning the shaft so that the crank and disc are eccentric to the bar a predetermined extent.

11. A device as in claim 10, with means between the bar and said shaft turning means 110

for then enabling the bar and shaft to be rotated as a unit.

12. Means for cutting a tubular member into lengths including a support for the member, a turnable bar, means supporting the bar axially of the supported member for movement into the member from one end thereof, a cutting disc at the outer end of the bar, said disc being smaller than the diameter of the member, means mounted in unitary connection with the bar for supporting said disc and means provided and formed in part with the disc supporting means for placing the disc eccentric with the bar and for then rotating the latter, or for placing the disc concentric with the bar selectively.

In testimony whereof I affix my signature.
